UNITED STATES PATENT OFFICE.

MARTIN L. BEISTLE, OF SHIPPENSBURG, PENNSYLVANIA.

GARLAND OR FESTOON.

1,247,361.

Specification of Letters Patent.

Patented Nov. 20, 1917.

Application filed August 10, 1917. Serial No. 185,622.

To all whom it may concern:

Be it known that I, MARTIN L. BEISTLE, a citizen of the United States, residing at Shippensburg, in the county of Cumberland and State of Pennsylvania, have invented certain new and useful Improvements in Garlands or Festoons, of which the following is a specification.

This invention relates to garland or festoon decorations comprising a cord and a package of decorative material loosely mounted thereon and consisting of end members and intermediate members, the intermediate members being secured to each other and to the end members in such manner that when the end members are pulled apart the package or bunch of intermediate members will be extended after the manner of accordion plaiting.

20 The adjacent intermediate members of such a garland are ordinarily connected together, as by pasting at regular intervals adjacent and between their edges, and I propose to insert and secure between certain of the adjacent members a flat member which is to serve as a hanger for a flat emblem, flag or other device; and one of the important features of my invention is to provide a form of connection between the hanger and the suspended emblem which insures that when the garland is in its extended condition the emblem will hang therefrom with its face parallel to the line of extension of the garland.

35 Other objects and aims of the invention, more or less broad than those stated above, together with the advantages inherent, will be in part obvious and in part specifically referred to in the course of the following 40 description of the elements, combinations, arrangements of parts, and applications of principles constituting the invention; and the scope of protection contemplated will appear from the claims.

45 In the accompanying drawings, which are to be taken as part of this specification, and in which I have shown merely a preferred form of embodiment of the invention, Figure 1 is an elevation of an extensible 50 tissue paper festoon or garland, in its extended condition and illustrating flat drops or ornaments suspended therefrom and with its face parallel to the line of extension of the supporting garland; Fig. 2 is a view 55 similar to Fig. 1, but showing the suspended drop turned at right angles from its po-

sition of Fig. 1; Fig. 4 is a view similar to Fig. 3, but with the supporting garland in compacted condition; and Fig. 5 is an enlarged detail of part of a garland, with a flat drop suspended therefrom.

Referring to the numerals on the drawings there is shown at 5 an extensible garland made of a plurality of sheets of tissue paper suitably shaped, colored and embellished, connected together adjacent their edges and preferably between the edges, so as to form when extended a honeycomb structure and when compacted to lie flat one upon the other. These tissue paper sheets 60 are usually secured together by pasting, and a supporting cord 6 runs through them all. Relatively stiff end members 7 complete the garland, which it may be stated, is as thus far described, of a known construction.

According to my present invention I insert at intervals in the length of the garland, hangers 8, which are merely flat members pasted between adjacent tissue paper sheets 80 and having a slotted projection 9 extending well beyond the edges of the tissue paper sheets between which it is held. A flat emblem or ornament, such as a flag, or shield, or star, or other device is indicated by the 85 numeral 10, and is provided with a vertical slot 11, with which the vertically slotted projection 9 of the hanger is engaged. When the garland is extended, the normal 90 tendency of the emblem 10 will be to assume the position shown in Figs. 1 and 5, that is, at a right angle to the hanger 8, but parallel to the line of extension of the garland. The result of this form of connection between the suspended emblem or 95 ornament and the garland is that the emblem will be parallel with the line of extension of the garland so that it will be clearly visible. When, however, the garland is compacted, as for transportation or storage, the emblem may readily be turned on its hanger to the position shown in Figs. 3 and 4, when it will be parallel to the hanger 8, and to the tissue paper sheets which make up the garland. The advantage of this for packing and transportation is obvious.

I conceive it to be of the essence of my invention that an extensible garland of the kind referred to has suspended from it a flat emblem or ornament with a connection between them such that in the use of the

garland the suspended flat emblem or ornament normally takes a position with its face parallel to the line of extension of the garland, but may be readily manipulated to bring it parallel to the individual sheets of paper making up the garland, that is to say, transverse to the line of extension. Other forms of connection than that illustrated may be employed.

10 Inasmuch as many changes could be made in the above construction, and many apparently widely different embodiments of my invention could be made without departing from the scope thereof, it is intended
15 that all matter contained in the above description or shown in the accompanying drawings shall be interpreted as illustrative and not in a limiting sense.

It is also to be understood that the language used in the following claims is intended to cover all the generic and specific features of the invention herein described and all statements of the scope of the invention which, as a matter of language, might be said to fall therebetween.

I claim:

1. A device of the kind described, comprising an extensible garland including a plurality of members connected together to form an extensible structure, said members lying flat upon each other when the structure is compacted, and a flat ornament or drop suspended from the structure and having a normal position when the garland is extended in which its face is parallel with the line of extension of the garland and capable of being moved so that its face will be transverse to the line of extension of the garland.

40 2. A device of the kind described, com-

Copies of this patent may be obtained for five cents each, by addressing the "Commissioner of Patents, Washington, D. C."

prising an extensible garland including a plurality of members connected together to form an extensible structure, said members lying flat upon each other when the structure is compacted, a hanger secured to the structure, and a flat ornament or ~~drop~~ suspended from said hanger and having a normal position when the garland is extended in which its face is parallel with the line of extension of the garland and capable of being moved relatively of the hanger so that its face will be transverse to the line of extension of the garland. 45 50

3. A device of the kind described, comprising an extensible garland including a plurality of members connected together to form an extensible structure, said members lying flat upon each other when the structure is compacted, a hanger secured between adjacent members, and a flat emblem or ornament suspended from said hanger and having a normal position when the garland is extended in which its face is parallel with the line of extension of the garland and capable of being moved relatively of the hanger so that its face will be transverse to the line of extension of the garland. 65

4. A device in accordance with claim 3 in which the hanger is a flat member provided with a slotted projection extending beyond the edges of the members between which it is secured, and in which the flat emblem has a slotted portion engaging with said slotted projection. 70

In testimony whereof I affix my signature 75
in the presence of a witness.

MARTIN L. BEISTLE.
